Application June 14, 1944, Serial No. 540,260

23 Claims. (Cl. 92—44)

1

The present invention relates to the placing of a forming wire on a paper making machine, and specifically deals with the draping of a forming wire in an open loop in the aisle adjacent the wet end of a Fourdrinier paper machine and the moving of this open loop into the line of the machine around the entire table thereof or around the couch roll only thereof.

It is one of the principal objects of the present invention to simplify the construction of a wire stringing device for a paper making machine and to improve the efficiency, operation and dependability of such wire stringing device.

Another principal object of this invention is to provide apparatus whereby the stringing of the wire in a paper making machine may be accomplished entirely from an overhead assembly, suspended from tracks, and adapted to be shifted from the aisle to the line of the machine where the stringing operation is performed. This arrangement permits the wire bundle to be assembled on the suspension means and made ready for stringing in the aisle before shutting down the machine. Also the aisle at the front side of the machine will be clear for access to the machine after the wire has been moved into the line of the machine.

A further object of the invention contemplates the provision of a wire stringing device having means that will bodily support or suspend the front end of a couch roll to provide a gap thereunder that is utilized during the stringing operation for passing an open bight of the wire bundle therethrough to position the bight in encompassing relation to the couch roll. The devices for suspending the couch roll are above the roll at a desirable location between the adjacent edge of the wire loop and the front end of the couch roll, and during the encompassing of the couch roll the wire loop is adapted to telescope the suspension devices and pass beyond said devices to a position where the loop encompasses the couch roll.

Another object is to provide a wire stringing structure that is adapted to suspend the table of a paper machine when its front end supports are displaced to open a gap therebetween through which the wire is passed to its encompassing relation around the table.

Still another object is to provide a wire stringer upon which the wire is assembled in an aisle, whereby the stringing operation may be performed upon either of two paper machines having their front sides at opposite sides of the aisle.

It is also an object to provide a wire stringer

whereon the wire bundle may be completely unwound and opened or extended in a manner that permits the encompassing of the entire table by the wire when the stringer has been moved into the plane of the line of the paper machine. This may be readily performed without removal of the forming table from its normally operating position.

It is another object of the invention to provide a traveling crane structure to carry the support for a wire bundle, which support is also adapted to suspend the front end of the couch roll. A portion of this bundle support is adapted for bodily moving the wire bundle from an initial position in the aisle at the front of the paper machine to a position within the confines of the main frame thereof or in the line of the paper machine, and after a gap beneath the front couch roll bearing has been closed the roll is disconnected from its suspension means and the latter is removed from the bundle support.

The invention contemplates providing an overhead crane structure with a removable frame that will support the table during transfer of the wire from an aisle position to a table encompassing position and is then adapted to be dismounted from the crane for removal bodily from the machine. This removable frame is provided with means that permit it to have rolling support upon the table members after being dismounted.

Another object of the invention is to provide a removable beam for supporting a wire bundle with an end portion of the wire disposed in a pendent loop prior to and during the encompassing of the couch roll with the wire loop. This beam is suspended in a removable manner that allows it to be readily removed longitudinally through the wire loop with an end portion supported by and riding upon the couch roll.

A further object is to provide mobile means for supporting the table or the front end of the couch roll during the encompassing operation, such mobile means being movably mounted upon the flanges of an angle metal frame or support that carries the wire bundle. The mobile means is preferably of the wheeled dolly type that is ridable on flanges of the bundle supporting device, during the movement of the supporting device to position the wire loop around the table, or couch roll, or both. The dolly is adapted to remain in a fixed relation to the table or couch roll to suspend it while the wire loop passes through a gap beneath the front end of the table or roll.

Another object of this invention resides in providing an overhead crane structure of such dimensions that it extends at least the length of the table and has provision for unrolling the wire bundle in the aisle and, after a gap has been opened beneath the table, the wire may then be transferred from its aisle position to a position encompassing the table the full length of the latter.

A still further object is to provide a wire stringer that is adapted to suspend the wire in a large open loop supported upon a traveler or crane for readily stringing the wire upon a cantilever type of Fourdrinier table.

The structure herein contemplated will conserve man power; it materially reduces the time that has heretofore been consumed in the operation of stringing the forming wire upon the couch roll and table of a paper making machine; it eliminates some of the usual steps heretofore required; and it dispenses with some of the parts of the prior devices.

Additional objects, aims and advantages of the invention contemplated herein will be apparent to persons skilled in the art after the construction and operation of the wire stringing or band stringing device is understood from the within description.

It is preferred to accomplish the numerous objects of this invention and to practice the same in substantially the manner hereinafter fully described and as particularly pointed out in the appended claims, reference being made to the accompanying drawings that form a part hereof.

Figure 1 is a vertical elevation of the wire stringing device in connection with a couch roll of a paper making machine, the forming wire bundle and looped portion thereof being in suspension above the aisle at the front of the machine;

Figure 2 is a vertical elevation showing the wire stringing device moved to a position where the wire loop has encompassed the couch roll;

Figure 3 is a vertical elevation showing the parts in the position shown in Figure 2 except that the gap at the front end of the couch roll has been closed and the supporting beam for the wire bundle is being removed from the loop, one end of the beam resting upon the couch roll;

Figure 4 is a diagram looking at the side of the assembly with the wire stringing devices in the position shown in Figure 2; and

Figure 5 is a diagram of the side of the assembly shown in Figure 3 with the bundle supporting beam being removed from the loop.

Figure 6 is a diagrammatic view in side elevation illustrating the wire being strung after it has encompassed the couch roll.

Figure 7 is an elevation of a wire stringer adapted to string the wire upon the forming section of a paper machine having a non-removable table portion.

Figure 8 is a front side elevation of the forming table and wire stringer shown in Figure 7.

Figure 9 is a fragmental transverse section of an aisle between paper making machines having forming tables of the cantilever type and illustrating a wire stringer suspended in the aisle ready to string the wire upon the table at the left.

Figure 10 is a front side view of the structure shown in Figure 9 after the wire has been strung on the table and the table front end supports have been replaced.

The drawings are to be understood as being more or less of a schematic character for the pur-

pose of disclosing a typical or preferred form of the improvements contemplated herein.

In the embodiment of the invention shown in Figures 1 to 6, the wire stringer is illustrated for draping the wire around a couch roll 10.

The couch roll 10 has its front end bearing 11 supported by a demountable block 12 that rests on a pedestal or the longitudinal side-sill 13 of the paper machine, the removal of said block being adapted to open up a gap 14 below the front end bearing of the couch roll that is utilized to pass the wire loop therethrough while stringing the wire loop upon the couch roll. The opposite end or rear end of the couch roll is supported by a bearing 15 mounted on the other side-sill 13a of the machine, and connections are made with the interior of the roll for sucking the moisture or condensation therefrom that is effected through a pipe or conduit 16.

The support for the wire bundle and for the couch roll front end comprises a horizontal beam 17 that is suspended by bars 18 from a cross rod 19, said bars 18 having hooks 51 at their lower ends that are engaged in holes in the upstanding lugs 17a adjacent the ends of the beam 17. This cross rod 19 has suitable connections at its end by means of links 20 with pulleys 21 around which the lower bights of cables 22 are reeved, the upper bights of said cables being reeved around pulleys 23 that are rotatably mounted at the ends of a traveling carriage or crane 24. For the purpose of operating the fall ends of cables 22, these ends are attached to and wound upon a rotatable drum 25 that is journaled in the central portion of the carriage or crane 24, and a motor 26 is provided driving said drum 25.

The carriage or crane 24 is provided with a plurality of rollers 27 that are engaged with the bottom flange of a horizontal beam 28 to support the crane in an overhead manner. This arrangement permits the crane to travel in longitudinal directions on the beam 28 to move the bundle supporting beam 17 in directions that are parallel to the axis of the couch roll 10.

The ends of the horizontal beam 28 are provided with hangers 29 of substantially U-shape that have rollers 30 journaled in their spaced upper ends. Horizontal tracks 31 of I-beam shape are mounted upon the ceiling or other overhead support and the rollers 30 of the hangers 29 travel on the lower flanges of these tracks, thus permitting the crane structure that suspends the bundle support to travel longitudinally with respect to the line of the paper making machine 55 and in a direction transverse to the axis of the couch roll 10. Thus the wire bundle may be conveniently assembled on its support with its pendent loop L in the aisle at the front end of the couch roll in readiness to encompass the roll 60 before the paper machine is shut down and the old forming wire removed therefrom.

The beam 17 is adapted to support the front end of the couch roll in a suspended manner when the block 12 has been removed from beneath the front end bearing 11 to effect the gap 14 thereunder. The means for suspending the front end of the couch roll comprises a dolly 32 having rollers 33 that ride on the lower flange of the I-beam 17. The lower portion of the dolly is provided with a shackle bolt 34 to carry a hook 35 that is engageable with an eye 36 on the upper segment of the couch roll end bearing 11. When the beam 17 and the wire bundle support moves in a direction axially of and above the couch roll to position the bundle and its open loop in encom-

passing relation to the couch roll, the dolly 32 will remain in a fixed or stationary position by riding upon the flange of the beam 17.

The ends of beam 17 are detachably connected by eye-bolts 60 to pole chucks 37 from which the apertured lugs 17a project. These chucks 37 rotatably carry spindles 37a with clamps 37b on their inner ends to clamp the ends of the two spool poles of the wire bundle. A looped end portion of the bundle depends upon opposite sides of the beam 17. The pole chucks 37 have laterally disposed horizontal arms 38 projecting from it adjacent the lugs 17a and the ends of these arms 38 have pocket-like seats 39 to receive the ends of spreader poles 40. These spreader poles 40 are employed to distend the upper portion of the wire loop far enough away from the beam 17 so that the pendent sides of the loop will be in vertical planes far enough apart to escape the front end bearing 11 of the couch roll when the wire loop passes through the gap 14 beneath said front bearing of the roll. Other spreader bars or poles 41 are positioned in the lower portion of the wire loop and are held in spaced relation to each other by horizontal bars 42 that are provided with concave seats 43 at their ends to receive said spreader poles 41. In this manner a wire loop is formed that has a rectangular shape such as shown in the diagram in Figure 4, the horizontal dimensions of which are large enough to accommodate the couch roll 10 and its front bearing 11 when the beam has been moved into the line of the machine and above the couch roll by passing the lower distended portion of the loop through the gap 14.

After encompassing of the couch roll 10 with the loop L of the wire, the block 12 is replaced beneath the front end bearing 11 of the couch roll to close the gap 14, and the pole chucks 37 and the beam 17 are lowered to permit the dolly 32 to be unhooked and released from the couch roll bearing 11 and then removed from the beam 17 by riding the dolly off the adjacent end of said beam at the aisle.

With the couch roll now restored to its initial position, the forming wire is ready to be strung upon the remaining portion of the paper making machine table by moving the crane devices of the overhead structure longitudinally of the line of the machine. Prior to doing this, however, the beam 17 is dismantled from its suspension devices by detaching the eye-bolts 60 to release the beam from the pole chucks 37 and then moving the beam forwardly in the loop of the wire to allow the beam to pass out of the loop in a direction axially of the couch roll 10. For the purpose of facilitating this removal, the beam 17 has secured to its rear portion, an inverted V-shaped bracket, the diverging arms 44 of which straddle the beam 17 (Figure 4) and carry obliquely disposed rollers 45 at their lower ends. These rollers are adapted to ride upon the top of the couch roll to support the beam until its rear end arrives at the front end of the couch roll where the beam may be readily lifted out of the way.

The arms 38, which support the spreader poles 40 for the purpose of suspending the loop of the wire, are a part of the pole chucks 37 that carry the bundle of wire and are therefore not removed with the beam 17. The vertical suspension bars 18 and hooks 51 are replaced by rods 18a having rings 51a at their lower ends to carry diverging links 46 which are engaged in holes 47 in the pole arms 38, in the manner shown in Figure 5.

The wire bundle spool poles have their ends

clamped in the chuck block carried spindles 37a and hand wheels 48 are provided for rotating the spindles and the spools to unwind portions of the wire bundle wound on the spools. Small brake bands 49 engage hub portions of the hand wheel to prevent unauthorized rotation of the spool poles and the wire bundle.

Preparatory to starting the wire stringing operation the carrier is positioned as shown in Figure 1 above the aisle with the wire loop L distended and opposite the front end of the couch roll. The dolly is moved along the I-beam until its hook can be engaged with the eye on the front end bearing of the couch roll, and thereupon the hanger cables are operated to elevate the carrier until the end of the roll is supported sufficiently to permit displacement of the removable block. The carrier assembly together with the pendent opened wire loop is moved in a direction longitudinally of the couch roll until the position shown in Figure 2 is reached, thus encompassing the couch roll with the wire loop. The block is then replaced under the front bearing of the couch roll and the hanger cables are operated to lower the beam 17 and restore the front bearing of the couch roll to its original or normal position so that the dolly may be unhooked from the bearing. The beam is then uncoupled from the chuck blocks so that it can be lowered until the rollers rest upon the top of the couch roll upon which the end is supported during the withdrawal of the beam out of the loop. A pole basket 52 (shown in Figure 6) is attached to the bottoms of the chuck blocks 37 with a plurality of poles 53 therein and the spreader bars 41 with their brackets 42 are removed from the looped wire. The stringer device may then be moved longitudinally of the machine to string the wire as shown in Figure 6 while temporarily stringing the upper bight of the wire upon poles 53 that have been removed from the basket 52 and suspended on hangers 54.

The wire stringers shown in Figures 7 to 10 embody structures for supporting the wire in an elongated loop that is approximately the length 45 of the forming table and, after the gap has been opened up beneath the front end of the table, this elongated wire loop is moved from an aisle position to a position in the line of the paper making machine to encompass the table. In these structures the front end of the forming table is supported during the stringing operation in one instance by the wire stringing assembly and in the other instance by a cantilever arrangement at the rear end support. In both types the wire is assembled in an elongated loop in the aisle at the front end of the forming table while the machine is in operation, thus eliminating a considerable loss of time in shutting down the machine during the wire stringing operation.

60 The forming table shown in Figures 7 and 8 comprises front and rear sills 61 and 62 respectively that extend longitudinally of the machine and support a plurality of table rolls 63 and the suction boxes 64. The breast roll 65 at the 65 ceiling end of the table is of the displaceable type that is fulcrumed upon a pivot 66 and has supporting arms 67 connecting it to the pivot to adapt the breast roll 65 for swing movement in a downward direction in the manner shown in 70 dotted lines in Figure 8. The suction couch roll 68 at the other or delivery end of the table is mounted for rotation in fixed relation to the table sills 61 and 62, and it has a front end bearing support 69 that is displaced to open up a gap between the couch roll and its pedestal 70. The

front end still 61 of the table is supported upon a plurality of pedestals 71 that are bodily removable, as shown in Figure 7, to open up a gap beneath the table at its front end. The wire when operating upon this table is held taut by a tension roller 72 journaled in bearings at the ends of a cross piece 73 that is connected by parallel links 74 having their ends pivotally connected to said cross piece and to brackets 75 depending from the under side of the table. This arrangement permits the tension roller to be shifted from the full line position in Figure 8 to the dotted line position thereon during the stringing operation.

The wire stringer assembly shown in Figures 7 and 8 comprises elongated side sills 76 that are spaced apart approximately the width of the forming table and are connected by a pair of converging bars 77 to eyes 78 at the lower ends of links 79 depending from an overhead crane structure such as shown in detail in Figures 1 and 2. The ends of the side sills 76 have oblique portions 80 and 81, respectively, that incline downwardly in opposite directions away from each other toward the respective ends of the table. Extension bars 82, 82 have curved upper portions that are secured to the inclined ends 80 of the side sills 76. Extension bars such as 83 are secured to the oblique ends 81 of the sills and have downwardly curved lower portions that extend around the ends of couch roll 68 and in spaced relation thereto. Clamps 84, 84 of U-shape are mounted on the bars 82 in the manner shown in Figure 8 to receive the loop-forming poles 85. Similar U-shaped clamps 86, 86 are secured to the curved bars 83 to support other loop-forming poles 87, 87. The side sills 76, 76 are preferably of angular cross section, preferably of the channel type and between their flanges these side sills have seats 88, 88 to receive poles 89, 89 that extend between the respective side sills 76.

The wire bundle has its spool poles clamped to spindles 90 rotatably carried by the intermediate portions of each of the side sills 76, 76. The spindles 90 have hand wheels 91, 91 to unwind the wire upon the carrier while the latter is above the aisle at the front end of the paper making machine forming table. The wire as shown in dotted lines in Figure 8 is trained upon the poles 89, 85 and 87 in the form of an open loop sufficiently elongated to encompass the table and couch roll when the breast roll is dropped to its foreshortened position. This elongated loop of the wire is maintained against slipping on the poles and its bights are kept taut in the position shown in dotted lines in Figure 8 by brake members 92 that operate upon the hubs of the hand wheels 91.

The means for supporting the front side of the table, to establish and maintain a gap beneath the table and couch roll, comprises a demountable structure that is carried by the side sills 76. This demountable structure comprises spaced I-beams 93, 93 that are secured to the under portions of the lower flanges of the side sills in the manner shown in Figure 8 by means of eye-bolts 94, 94. The ends of these I-beams 93 are connected to transverse I-beams 95, 95, the lower flanges of which provide tracks for traveling dollies 96, 96. The upper portions of these dollies 96 are of yoke shape for mounting confronting tapered rollers 97, and the lower ends of these dollies are provided with clevis hooks 98, 98 to engage in eyes 99, 99 on the upper surface of the front end members 61 of the forming table. When the hooks 98 have been engaged in the manner described the front end of the table may be lifted

by operating the winding drum 25 on the crane structure to thereby lift the front end member 61 of the table for the removal of the pedestals 71 and the end bearing block 69 for the couch roll, thus providing a gap at the front end of the forming table.

After the loop has been made with the wire above the aisle at the front end of the forming table and the hooks 98 have been engaged with the eyes 99 on the forming table front member 61, the paper making machine is stopped and the gap beneath the front end of the table and the couch roll is then opened up and the breast roll is dropped to its lowered position (dotted lines in Figure 8). The loop assembly is then moved from its aisle position as shown in Figure 7 across the table until the wire loop has encompassed the table. The pedestals 71 and the front end bearing block 69 are then restored and the table is lowered to its normal operating position, after which the hooks are released from the eyes 99 and the dollies 96 are removed from the tracks 95.

The I-beam tracks 95, together with the beams 93, are now removed by loosening and turning down the eye bolts 94 permitting removal of these parts from the side sills 76 of the stringer. To facilitate removal of this portion of the wire stringer the beams 93 have brackets 100, 100 depending from their lower flanges that have rollers 101, 101 journaled in their lower ends. This arrangement permits the rollers 101 to ride on the top of the table while the beams 93 and 95 are being removed through the wire loop.

It will be understood that during the stringing operation the dollies 96 will remain in fixed relation to the front end of the forming table with their rollers 97 riding on the lower flanges of the I-beam track 95 while the stringer assembly is being moved from its aisle position to its table, encompassing position in the line of the paper making machine.

Figures 9 and 10 disclose the manner of using a wire stringer such as contemplated herein on a cantilever type of forming table in a Fourdrinier paper making machine. As shown in Figure 9 there is an aisle A between the front sides of longitudinally extending paper making machines, designated generally as B and C, and the front ends of the forming tables are supported by removable pedestals such as 71a. The rear portions of the table are supported on pedestals 71b and extend past the same a suitable distance where the table portions are engaged by upstanding bars 102 having nuts 103 screwed upon their threaded upper ends. By tightening these nuts 103 the forming table will be cantilevered upon the rear side pedestals 71b as fulcrums so that the front pedestals 71a may be removed to open a gap under the table. The wire stringer is assembled in the aisle A between the front sides of the respective tables and the overhead crane structure is so arranged that the stringer may be used upon either the table B or the table C, depending on which table the wire is to be strung. In the present instance the left-hand table B is ready to be strung with the wire. Other portions of the forming table shown in Figure 10 are identical with those shown in Figure 8 and therefore, in the interest of simplicity, the corresponding reference characters are applied to the parts in Figure 10 that are common to parts in Figure 8.

In view of the cantilever type of support for the forming table shown in Figure 10, the gap at the front side of the table need not be maintained

by means of dollies and the underframing that is detachably mounted upon the side sills of the stringer shown in Figure 8. The wire stringer shown in Figure 10 is supported by cable links 77a that are attached at their upper ends to the overhead traveling crane structure for permitting the shifting of the wire stringer across the table to encompass the wire around the table member. The ends of the side sills 76a have downwardly extending bars 82a and 83a, and poles 85a are carried on the bars 82a by means of the U-shaped clamp 84a. Similarly, poles 81a are secured to the bars 83a by U-shaped clamp members 86a. Seats 88a are provided upon the facing inner portions of the side sills 76a to receive the pole 89a between the sills, and the spool poles of the wire bundle are clamped to the spindles 90a for rotation by the hand wheels 91a that are braked by bands 92a. In this construction and arrangement the wire is trained upon the poles 85a, 81a and 89a in the manner shown in dotted lines in Figure 10, such arrangement being the same as the arrangement shown in Figure 8. The assembly of the wire in a loop upon the stringer device is made in the aisle prior to shutting down the machine. After the machine has stopped the front end of the forming table is cantilevered upwardly to remove the pedestals 11 and couch roll bearing support 69 at its front ends to open the gap and permit passage of the lower run of the loop of wire through said gap for encompassing the forming table.

From the above descriptions it will be understood that the invention provides apparatus for rapidly placing a forming wire on a Fourdrinier machine without damaging the wire since the wire is not dragged over any supports even though the paper machine does not have a laterally movable table.

I claim as my invention:

1. In combination, a paper making machine of the Fourdrinier type having a couch roll with a removable front bearing support for opening up a gap facilitating passage of a forming wire, a movable wire bundle carrier, means suspending said carrier above the couch roll for movement longitudinally and laterally of the machine, spreader poles on said carrier for holding a portion of a forming wire from a bundle on the carrier in an open depending loop large enough to freely encompass the couch roll, a mobile device movable longitudinally on said carrier in said loop for suspending the front of the couch roll to maintain the aforesaid gap, and said suspending means arranged to move the carrier for conveying the open wire loop thereon from a position laterally of the machine into the line of the machine to encompass the couch roll while said mobile device moves on the carrier within the loop.

2. In combination a paper making machine of the Fourdrinier type having a couch roll with a removable front bearing support for opening up a gap accommodating passage of a forming wire, an overhead crane movable longitudinally and laterally of the machine, a wire bundle carrier suspended from said crane, spreader poles on said carrier for holding a portion of a forming wire from a bundle on the carrier in an open depending loop large enough to freely encompass the couch roll, a dolly movable longitudinally on said carrier in said loop for suspending the front of the couch roll to maintain said gap, and said crane arranged to move the carrier laterally for conveying an open wire loop thereon

into the line of the machine to encompass the couch roll while said dolly rides on the carrier within the loop.

3. In combination, a paper making machine of the Fourdrinier type having a couch roll with a removable front bearing support for opening up a gap accommodating passage of a forming wire, an overhead crane movable axially of the couch roll, tracks guiding said crane for movement longitudinally of the machine, a wire bundle carrier suspended from said crane, spreader poles on said carrier for holding a portion of a forming wire from a bundle on the carrier in an open depending loop large enough to freely encompass the couch roll, a dolly movable longitudinally on said carrier in said loop for suspending the front of the couch roll to maintain said gap, and said crane arranged to move the carrier for conveying an open wire loop thereon laterally into the line of the machine to encompass the couch roll while said dolly rides on the carrier within the loop.

4. In combination, a paper making machine of the Fourdrinier type having a couch roll with a removable front bearing support for opening up a gap accommodating passage of a forming wire, an overhead crane movable axially of the couch roll, elongated supports for guiding said crane for movement lateral to the axis of the couch roll, a beam for supporting a wire bundle, pendent means connecting said beam to said crane for movement therewith, means on said beam for holding a portion of a forming wire from a bundle on the carrier in an open depending loop large enough to freely encompass the couch roll, and a mobile device movable longitudinally on said beam in said wire loop for suspending the front of the couch roll to maintain said gap, said crane arranged to move said beam for transferring the open wire loop thereon from a position adjacent the front of the machine to a position in the line of the paper machine to encompass the couch roll while said mobile device moves on said beam within the loop.

45 5. A wire stringer for a Fourdrinier paper making machine having a couch roll with a front bearing support that is movable for effecting a gap for passage of a forming wire therethrough, carrier devices adapted for movement in a plurality of directions above the paper making machine and an aisle along the front side thereof, said carrier devices comprising a horizontal beam assembly connected to overhead traveler means, seats on said beam for supporting a wire bundle, spreader poles for holding a portion of a forming wire bundle in a depending loop in front of the couch roll, a dolly for suspending the front of the couch roll to maintain the aforesaid gap, said beam and dolly adapted for relative movement the one with respect to the other whereby the loop of the wire bundle is passed through said gap and is encompassed around the couch roll, and said beam and poles constituting a unitary structure that is removable through the wire loop 60 in a direction longitudinally of the axis of the couch roll.

6. A wire stringer for a Fourdrinier paper making machine having a couch roll with a removable front bearing support for effecting a gap for passage of a forming wire therethrough, comprising overhead traveler devices adapted for longitudinal and transverse movement with respect to the line of the Fourdrinier table, vertically adjustable hangers depending from said traveler devices, a carrier assembly above the plane of the

paper machine to move with said traveler devices, said assembly comprising a horizontal beam detachably connected to said hangers for supporting the forming wire bundle, spreader poles carried by said beam for supporting a portion of a wire bundle in a distended loop that is adapted to encompass the couch roll, and a dolly on said beam effective for supporting the couch roll to maintain the aforesaid gap, said beam and dolly adapted for relative movement the one with respect to the other to pass the wire loop through said gap and encompass the couch roll therewith.

7. A wire stringer for a Fourdrinier paper making machine having a couch roll with a removable front bearing support for effecting a gap for passage of a forming wire therethrough, comprising overhead traveler devices adapted for longitudinal and transverse movement with respect to the line of the Fourdrinier table; vertically adjustable hangers depending from said traveler devices, a carrier assembly above the plane of the paper machine to move with said traveler devices, said assembly comprising a horizontal beam detachably connected to said hangers for supporting the forming wire bundle, spreader poles carried by said beam for supporting a portion of a wire bundle in a distended loop that is adapted to encompass the couch roll, a dolly on said beam effective for supporting the couch roll to maintain the aforesaid gap, said beam and dolly adapted for relative movement the one with respect to the other to pass the wire loop through said gap and encompass the couch roll therewith, and said beam adapted for ready removal longitudinally through the wire loop, and rollers on said beam adapted to travel on said couch roll to support an end portion of said beam during removal.

8. A paper machine wire stringer comprising a beam, a support for a wire bundle on said beam, means associated with said support for holding an end portion of a wire from a bundle on said support in a depending loop having dimensions adapting the loop to encompass a couch roll, a couch roll supporting dolly movable lengthwise on said beam, and suspension means supporting said beam for longitudinal movement in a direction parallel with the axis of the couch roll whereby to bodily move the loop of the wire bundle from a position laterally of the machine into a position in the line of the paper machine to encompass the couch roll, said couch roll supporting dolly being adapted to remain in fixed relation to the end of the couch roll during movement of the beam into the line of the paper machine to suspend the end of the couch roll free of its normal support to maintain a gap thereat for passage of the loop of the wire bundle to its roll-encompassing position.

9. A paper machine wire stringer comprising overhead traveler devices adapted for longitudinal and transverse movement with respect to the line of the Fourdrinier table, vertically adjustable hangers depending from said traveler devices, and a carrier assembly above the plane of the paper machine to move with said traveler devices, said assembly comprising a horizontal beam detachable from said hangers, a support for a wire bundle on said beam, means associated with said support for holding an end portion of a wire from a bundle on said support in a depending loop having dimensions adapting the loop to encompass a couch roll, a couch roll supporting dolly movable lengthwise on said beam, the overhead traveler devices supporting said beam for longitudinal movement in a direction parallel with

the axis of the couch roll whereby to bodily move the loop of the wire bundle from a position beyond an end of the couch roll into a position in the line of the paper machine to encompass the couch roll, said couch roll supporting dolly being adapted to remain in fixed relation to the end of the couch roll during movement of the beam into the line of the paper machine to suspend the end of the couch roll free of its normal support to maintain a gap thereat for passage of the loop of the wire bundle to its roll-encompassing position.

10. A wire stringing device for a paper making machine having a couch roll with a front bearing support that is removable to form a gap beneath the bearing, comprising a horizontal beam for supporting a wire bundle with an end portion formed in a pendent loop that is suspended in an aisle at the front of the machine; a traveler crane movable in a plurality of directions with respect to the line of the paper making machine, said crane connected to said beam whereby a movement of the crane in a direction transverse to the line of the machine is effective to transfer of the wire bundle and the loop thereof from a position in the aisle to a position in the line of the paper making machine; and a dolly on said beam for suspending the front end of the couch roll to maintain the aforesaid gap beneath the front bearing of the couch roll, said dolly and beam adapted for relative movement one with respect to the other whereby the dolly is held in a fixed suspending position with respect to the couch roll during the aforesaid transfer of the wire bundle and the loop.

11. A wire stringing device for a paper making machine having a couch roll with a front bearing support that is removable to form a gap beneath the bearing, comprising a horizontal beam for supporting a wire bundle with an end portion formed in a pendent loop that is suspended in an aisle at the front of the machine; a traveler crane supported above the paper machine for movement longitudinally thereof, said crane connected to said beam and having movement in a direction axially of the couch roll to effect the transfer of the wire bundle and the loop thereof from the position in the aisle to a position in the line of the paper making machine; and a dolly on said beam for suspending the front end of the couch roll to maintain the aforesaid gap beneath the front bearing of the couch roll, said dolly and beam adapted for relative movement one with respect to the other whereby the dolly is held in a fixed suspending position with respect to the couch roll during said transfer of the wire bundle and the loop.

12. A wire stringing device for a paper making machine having a couch roll with a front bearing support that is removable to form a gap beneath the bearing, comprising a horizontal beam for supporting a wire bundle with an end portion formed in a pendent loop that is suspended in an aisle at the front of the machine; a traveler crane movable above the table of the paper machine; overhead tracks extending longitudinally of the paper making machine for movably suspending the crane, said crane connected to said beam and movable in a direction transverse to said overhead tracks whereby to effect the transfer of the wire bundle and the loop thereof from the position in the aisle to a position in the line of the paper making machine; and a dolly on said beam for suspending the front of the couch roll to maintain the aforesaid gap beneath the front bearing of

the couch roll, said dolly and beam adapted for relative movement one with respect to the other whereby the dolly is held in a fixed suspending position with respect to the couch roll during said transfer of the wire bundle and the loop.

13. A device for encompassing a roll with a looped band, comprising a band support; means on said support for holding a portion of the band in an open depending loop; a movable suspension device for said support adapted to move in a direction to carry the open loop on the support from a position beyond an end of a roll to a position encompassing the roll; and a dolly movable on said support for suspending an end of the roll to maintain a gap thereunder to facilitate passage of the loop during movement of the support in a direction longitudinally of the roll.

14. A device for encompassing a roll with a looped band, comprising a suspended horizontal beam supporting the band; means on said beam for holding a portion of the band in an open depending loop; a traveler crane supporting said beam, said crane adapted to move in a direction to carry the open loop on the beam from a position beyond an end of a roll to a position encompassing the roll; and a dolly movable on said beam for suspending an end of the roll to maintain a gap thereunder to accommodate passage of the loop during movement of the beam in a direction longitudinally of the roll.

15. A device for encompassing a roll with a looped band, comprising a band support; means on said support for holding an end portion of the band in an open depending loop; an overhead traveler crane suspending said band support for movement in a direction axially of the roll to carry the open loop from a position beyond an end of a roll to a position encompassing the roll, said traveler crane also having movement transverse to the axis of the roll to string the remaining portion of the band away from the roll; and a dolly movable on said band support for suspending an end of the roll to maintain a gap thereunder to accommodate passage of the band loop during movement of the support in a direction longitudinally of the roll.

16. A wire stringing apparatus for a Fourdrinier paper making machine having a couch roll with a removable front bearing support, said apparatus comprising overhead traveler devices adapted for movement in longitudinal and transverse direction with respect to the couch roll; vertically adjustable hangers depending from said traveler devices; and a carrier assembly suspended by said hangers from said traveler devices for movement therewith above the paper making machine, said carrier assembly comprising a horizontal elongated beam detachably connected to said hangers; seats on said beam for supporting a wire bundle with a portion of the wire formed in a pendant loop opposite the front of the couch roll; spreader poles on said beam for distending the wire loop into dimensions large enough to encompass said couch roll; a dolly adapted to traverse said beam and being demountable therefrom; and means detachably connecting said dolly to the front of the couch roll to effect a fixed relationship between the dolly and the couch roll whereby to suspend the couch roll front end from said beam between vertical planes defining the couch roll front side and the proximate edge of the wire loop thereby to open and maintain the gap beneath said front of the couch roll, said beam being adapted for movement independent of said dolly for effecting transfer of the wire bundle into

the line of the paper making machine by passing the loop of the wire through the gap to encompass the couch roll with the wire loop; said beam, seats, and spreader poles being adapted for removal longitudinally through the wire loop.

17. In combination, a paper making machine of the Fourdrinier type having a forming table with a removable front support for opening up a gap facilitating passage of a forming wire; a shiftable wire carrier; means on said carrier for holding the wire in a depending open loop at the front of said table; a device movable on said carrier in the wire loop for suspending the front of said table to maintain the aforesaid gap; and overhead traveler means suspending said carrier for movement to convey the wire loop from beyond the front end of said table into encompassing relation therewith while said front end suspending device moves on said carrier within the wire loop.

18. In combination, a paper making machine of the Fourdrinier type having a roll part with a removable front support for opening up a gap facilitating passage of a forming wire; a shiftable wire bundle carrier; means suspending said carrier in a plane above the plane of said roll part for shifting movement across said roll part, spreader poles on said carrier for holding a portion of a forming wire from a bundle on said carrier in an open depending loop large enough to freely encompass said roll part; and a device movable longitudinally of said carrier in said loop for suspending the front of said roll part to maintain the aforesaid gap, said suspending means arranged to move said carrier for conveying the open wire loop thereon from beyond the front end of said roll part into line therewith to encompass said roll part while said movable device moves on said carrier within the wire loop.

19. A paper machine wire stringer comprising longitudinal side members; a support for a wire bundle on said side members; spaced transverse beams detachably carried by said side members; means associated with said support and side members for holding the wire in a depending loop having dimensions adapting said loop to encompass a forming table; forming table supporting dollies movable lengthwise on said beams; and suspension means for supporting said side members and beams for movement across the forming table whereby to move the wire loop from a position beyond the front of the forming table into a position in the line of the paper machine to encompass the forming table, said table supporting dollies being adapted to remain in fixed relation to the front of the forming table during movement of the side members and beams into the line of the machine to suspend the front of the table free of its normal support to maintain a gap for passage of the wire to its table-encompassing position.

20. In combination, a paper making machine of the Fourdrinier type having a forming table with a removable front support for opening up a gap facilitating passage of a forming wire; a shiftable wire carrier; means on said carrier for holding the wire in an elongated depending open loop at the front end of said table and approximately the length thereof; tracks removably mounted on said carrier transverse to the wire loop; devices movable on said tracks within the wire loop for suspending the front of said table to maintain the aforesaid gap; overhead traveler means suspending said carrier and tracks for movement to convey the wire loop from beyond the front of said table into encompassing rela-

tion therewith while said front end suspending device moves on said tracks within the wire loop; and rollers pendently carried by said tracks adapted to travel on said forming table to support a portion of said tracks during endwise removal of said tracks through the wire loop.

21. In combination, a paper making machine of the Fourdrinier type having a forming table with a removable front support for opening up a gap facilitating passage of a forming wire; a shiftable wire bundle carrier; means suspending said carrier in a plane above the plane of said table for shifting movement across said table; spreader poles on said carrier for holding a portion of a forming wire from a bundle on said carrier in an open depending loop large enough to freely encompass said table; removable transverse beams on said carrier within the wire loop; devices movable longitudinally on said beams in said loop for suspending the front of said table to maintain the aforesaid gap, said suspending means arranged to move said carrier for conveying the open wire loop thereon from beyond the front of said table into line therewith to encompass said table while said movable devices move on said beams within the wire loop; and rollers on said beams adapted to travel on said table to support portions of said beams during removal of the beams through said wire loop.

22. In combination, a Fourdrinier paper making machine having a forming table with a removable front support for opening up a gap facilitating passage of a forming wire, a wire stringer comprising longitudinal side members; means supported by said side members for holding the wire in a depending loop having dimensions adapting said loop to encompass the forming table; spaced transverse beams detachably carried by said side members; dollies movable lengthwise on said beams having supporting connection with the front end of said forming table; overhead suspension means for supporting said side members for movement across said forming

table whereby to move the wire loop from a position beyond the front end of the forming table into a position in the line of the paper machine to encompass the forming table, said dollies being adapted to remain in fixed supporting relation to the front end of the forming table during movement of the side members into the line of the machine to maintain the aforesaid gap for passage of the wire to its table-encompassing position; and rollers having fixed connection with said transverse beams adapted upon detachment of said beams from said side members to support said beams out of contact with said forming table, said rollers also adapted to roll on said forming table to facilitate endwise removal of said beams through said wire loop.

23. A wire stringer for a paper making machine comprising a support for the spool poles of a wire bundle, devices carried by said support for holding wire of the bundle in an open loop, a detachable track on said support arranged to extend through said loop, and a paper machine roll suspension device rideable on said track whereby the support can carry a wire loop around a machine roll while the suspension device suspends the receiving portion of the roll and rides through the loop and whereby the track and suspension device are removable from the support for mounting the wire on the roll.
